Specification for Design.

Patented Jan. 30, 1917.

Application filed July 28, 1915. Serial No. 42,424. Term of patent 7 years.

To all whom it may concern:

Be it known that I, HARRISON CADY, a citizen of the United States, and resident of Brooklyn, in the county of Kings, city and State of New York, have invented a new, original, and ornamental Design for an Article of Manufacture, of which the following is a specification, reference being had to the accompanying drawings, forming a part thereof.

In the drawings I have shown a representation of a toy embodying my design.

Copies of this patent may be obtained for five cents each, by addressing the "Commissioner of Patents, Washington, D. C."

The design as shown comprises an ornamental figure in the form of a fanciful representation of a jay embodied in a toy, but I contemplate that the same may also be embodied in or applied to various other articles of manufacture.

I claim:

The ornamental design for an article of manufacture, as shown and described.

HARRISON CADY.
